AUTOMATIC IGNITION AND CONTROL
MECHANISM FOR OVEN BURNERS

Charles M. Mayer, Mansfield, Ohio, assignor to
The Tappan Stove Company, Mansfield, Ohio,
a corporation of Ohio

Application December 10, 1951, Serial No. 260,901

13 Claims. (Cl. 161—9)

1

This invention relates to an automatic electric ignition and control mechanism for cooking range burners using gaseous fuel and is a modification of the control mechanisms shown in the co-pending application of Charles M. Mayer Serial No. 200,203, filed December 11, 1950, now Patent No. 2,584,147, and the co-pending application of Charles M. Mayer and John M. Hoff Serial No. 153,664, filed April 3, 1950, now Patent No. 2,577,787. It is specifically designed and adapted for automatically igniting and controlling the operation of oven burners in cooking ranges, and may be used in conjunction with a time control mechanism or independently thereof as desired.

The mechanism is designed for use with a main gaseous fuel burner which is adapted to be ignited by a gaseous fuel pilot burner. As long as the pilot burner is ignited it is immaterial whether or not the main burner burns constantly. It may be extinguished for some reason, but it will be promptly re-ignited by the pilot burner if fuel is supplied thereto. But if the pilot burner is extinguished for any reason while the main control valve is still open to supply gas to the main burner a very dangerous situation sometimes arises. Let us assume that both the pilot burner and the main burner are extinguished during operation for some reason. Gas can then flow to the main burner but since the pilot burner is extinguished the main burner will not be ignited and unburned gas will accumulate in the oven which may violently explode when an attempt is made to ignite either the main or pilot burner. It has been found by experience that both the pilot burner and the main burner are frequently extinguished during use while the main control valve is open to supply gas to the main burner. This is sometimes due to a momentary failure of the gas supply or the slamming of the oven door, or to various other reasons.

In order to prevent any accumulation of unburned gas and thus eliminate any danger of an explosion therefrom in the event the pilot burner is extinguished for any reason while the control valve is still set to supply gas to the main burner, I provide in my improved apparatus safety control mechanism by which the supply of gas to both the main burner and the pilot burner is completely cut off, independently of the main control valve, in the event the pilot burner is extinguished for any reason while the main gas control valve is open.

My improved apparatus includes a main gaseous fuel burner by which the oven in a cooking range is heated. The main burner is adapted

5 to be ignited by a gaseous fuel pilot burner which burns only during the time the oven is in operation. At other times the supply of gas to both the main burner and the pilot burner is cut off by a main control valve which is interposed in a conduit between the gas supply manifold and the burners, and has two open positions and one closed position. In one open position the mechanism is set for manual control and in the other 10 open position the mechanism is set for automatic control by the time control mechanism. When the main control valve is open gas will flow from the manifold through the main control valve and into a safety control valve mechanism. From 15 the safety control valve mechanism gas will flow through a small branch conduit directly to the pilot burner; and through the main conduit and a standard thermostatically operated oven temperature control valve to the main burner. A normally open master control switch which is operatively associated with the main control valve is arranged to be closed by the opening of the main control valve and to be opened by the closing of the main control valve. The closing 20 of the master control switch, as the main control valve is opened to supply gas to the burners, energizes through a normally closed thermostatically operated switch an electric resistance ignition element and a solenoid which is operatively connected to the safety control valve mechanism. The energization of the solenoid causes it to operate the safety control valve mechanism to permit the flow of 25 gas to the pilot burner while cutting off the supply of gas to the main burner. The pilot burner is ignited by the electric ignition element and projects a flame against a thermostatic element, which controls the operation of the normally closed switch, and against a thermocouple which is operatively connected to the 30 safety control valve mechanism. The energization of the solenoid causes it to operate the safety control valve mechanism to permit the flow of gas to the pilot burner while cutting off the supply of gas to the main burner. The pilot burner is ignited by the electric ignition element and projects a flame against a thermostatic element, which controls the operation of the normally closed switch, and against a thermocouple which is operatively connected to the 35 safety control valve mechanism. After the thermostatic element becomes heated it opens the normally closed switch which de-energizes the electric ignition element and the solenoid. As soon as the solenoid is de-energized the safety control mechanism is automatically operated by spring means to supply gas to the main burner through the oven temperature control valve. The main burner is then ignited by the pilot burner. The thermocouple, as long as it is heated by the pilot burner, maintains the safety control valve mechanism in condition to supply gas to both the main burner and the pilot burner. The oven temperature control valve then regulates 40 the supply of gas to the main burner so

as to maintain the desired oven temperature. As long as the pilot burner is ignited the main burner will burn normally under the control of the oven temperature control valve until the main control valve is manually turned off. But if during operation the pilot burner is extinguished for any reason the thermocouple will immediately cool and allow the safety control valve mechanism to automatically cut off the supply of gas to both the main burner and the pilot burner. As an example of the manner of operation of the apparatus, let us assume that during operation the pilot burner is suddenly extinguished, for instance, by a momentary failure of the gas supply from the manifold to the burners. The thermocouple immediately cools, allowing the safety control valve mechanism to cut off communication between the manifold and both the main burner and the pilot burner. The main control valve is still open and the master switch closed. Then after the thermostatic element has cooled, closing the normally closed switch, which is maintained open by the thermostatic element during normal operation of the oven, the electric ignition element and the solenoid are again energized. The energization of the solenoid will cause it to operate the safety control valve mechanism to establish communication between the manifold and the pilot burner only. Then when gas is again available the pilot burner will be ignited and re-establish normal operation of the oven as previously described. In the event of a power failure during normal operation of the oven under manual control, the main burner will continue to operate normally under the control of the oven temperature regulator valve until the burner is turned off by the main control valve, assuming of course that the pilot burner continues to burn. In the event of a power failure before gas is turned on by the main control valve, the pilot burner can be manually ignited as will be hereinafter explained. The supply of gas to both the main burner and the pilot burner will then be controlled by the pilot burner through the thermocouple and safety control valve mechanism as previously described.

In order to adapt the mechanism for automatic control by a standard electrically operated time control mechanism I provide a bypass conduit around a portion of the main conduit between the manifold and the safety control valve mechanism with the main control valve located at a junction of the bypass conduit and the main conduit so that when it is in one open position it will direct fuel straight through the main conduit for manual control and when it is in the other open position it will direct fuel through the bypass conduit for automatic control. I also interpose a normally closed solenoid-operated valve in the bypass conduit, and I provide a supplemental master switch which is adapted to be closed by the setting of the main control valve for automatic operation and to be opened by the closing of the main control valve. The supplemental master switch is in series with the normally closed thermostatically operated switch and a normally open switch which is adapted to be opened and closed by the time control mechanism at predetermined set times. The solenoid which actuates the normally closed valve in the bypass conduit is also in series with the time control actuated switch. For automatic operation the time control mechanism is set to close the associated switch at a predetermined time and to open it at a prede-

terminated later time, and the main control valve is set to direct fuel through the bypass which closes the supplemental master switch. Then at the set time the time control mechanism will close the associated switch which will effect energization of the electric ignition element, the solenoid for actuating the time control mechanism and the solenoid for opening the normally closed valve in the bypass conduit. Fuel will then flow to the safety control valve mechanism and from there to the pilot burner where it is ignited by the electric ignition element. The mechanism will then function as previously described under control of the safety control valve mechanism and the oven temperature control valve until the time control mechanism opens the associated switch which effects closing of the normally closed valve in the bypass conduit thus cutting off the supply of fuel to both the main burner and the pilot burner.

The principal object of the invention is to provide an improved electrical ignition and automatic control system for cooking range oven burners using gaseous fuel.

Another object of the invention is to provide in an electrical ignition and control system of the character described improved means for completely shutting off the supply of gas to both the main burner and the pilot burner in the event the pilot burner becomes extinguished for any reason before the supply of gas to both the main burner and the pilot burner is cut off by the main control valve.

Another object of the invention is to provide an apparatus of the character described which is so constructed and arranged that food in an oven will be cooked the set length of time regardless of temporary current failure during operation.

Still another object of the invention is to provide an improved electrical ignition and control system of the character described which may be used in conjunction with a time control mechanism or independently thereof as desired.

Other and more limited objects of the invention will be apparent from the following specification and the accompanying drawing forming a part thereof, wherein:

Fig. 1 is a diagrammatic view illustrating my improved electrical ignition and safety control mechanism as applied to a cooking range oven burner using gaseous fuel;

Fig. 2 is an enlarged central longitudinal vertical section through the safety control valve mechanism showing the various parts in the position they assume when the oven burner is turned off;

Fig. 3 is a view similar to Fig. 2 showing the various parts in the positions they are automatically moved to when the main control valve is first turned on to initiate the operation of the main oven burner;

Fig. 4 is a horizontal section taken on the line 4-4 of Fig. 1;

Fig. 5 is a sectional view through the main control valve showing it in position to direct fuel straight through the main conduit;

Fig. 6 is a view similar to Fig. 5 showing the main control valve set to direct fuel through the by-pass conduit;

Fig. 7 is a view similar to Fig. 1 showing a slightly modified form of the invention; and

Fig. 8 is a view similar to Fig. 1 showing another modified form of the invention.

Referring now to the drawing by reference

characters, the numeral 1 indicates a gaseous fuel burner which is mounted in or in heating relation to a cooking range oven 2. Gaseous fuel is supplied to the burner 1 from a manifold M through a conduit 3. Interposed in the conduit 3 are a main control valve 4, a safety control valve mechanism generally indicated by the numeral 5, and an oven temperature control valve 6. The main control valve 4 is a cut-off valve of standard construction having two open positions and one closed position and which when in an open or on position permits the flow of gas from the manifold M to the burner 1, and in closed or off position cuts off flow of gas to the burner 1. This valve is manually opened and closed by a suitable handle and a valve stem 8, and directly controls the operation of the entire apparatus in that it initiates the operation of the entire apparatus when it is turned to an on position and terminates the operation when it is turned to the off position. From the main control valve 4 gas flows through the conduit 3 to the safety control valve mechanism 5, to be described in detail hereinafter. From the safety control valve mechanism 5 the gas flows through the conduit 3 and the oven temperature control valve 6 to the burner 1. The oven temperature control valve 6 is operative to regulate the amount of gas flowing to the burner 1 in order to maintain the oven at any desired set temperature. The valve 6 is set to any desired temperature by a handle 11 having a pointer 12 which cooperates with a graduated dial 13 carried by the valve 6. The valve 6 is controlled according to the temperature setting by a thermostatic element 14 which is mounted in the oven 2 and is connected to the valve 6 as shown at 15. The oven temperature control valve 6 is of standard well known construction. Consequently it is not shown in detail herein. There are many different constructions available any one of which will work equally well herein. Gas is also supplied to a pilot burner 16 through a branch conduit 17 which extends between the safety control valve mechanism and the pilot burner 16. The pilot burner 16 is disposed adjacent the rear end of the main burner 1 in position to ignite the burner 1 when gas is supplied thereto. An electrical ignition element 18 is operatively associated with the pilot burner 16 in position to ignite the pilot burner 16 when gas is supplied thereto. A thermostatic element 19 and a thermocouple 20 are mounted in position to be heated by a flame from the pilot burner. The thermostatic element 19 is operative to open and close a switch 21 which controls the energization of the electrical ignition element 18 and a solenoid 22 which when energized operates the safety control valve mechanism to supply gas to the pilot burner 16 as will be described in connection with the description of the safety control valve mechanism and the operation of the whole apparatus. The thermocouple 20 when heated is operative to hold the safety control valve mechanism in condition to maintain the supply of gas to both the pilot burner 16 and the main burner 1, as will also be described in connection with the description of the safety control valve mechanism and the operation of the apparatus. A master control switch 23 which is associated with the main control valve 4 is adapted to be opened and closed simultaneously with the closing and opening of the main control valve 4. As the control valve 4 is turned from the off or closed position to one on or open position the switch mechanism 23 is moved from

the open position to the closed position by an operating lever 24 which cooperates with a cam section 25 on the main control valve stem 8. Conversely, when the main control valve 4 is turned from the open or on position to the closed or off position the switch mechanism 23 is moved from the closed position to the open position. An electric circuit between the thermocouple 20 and the safety control valve mechanism 5 is established by a copper tube 26 which encloses an insulated wire 27.

The construction of the safety control valve mechanism 5 and its connection to the solenoid 22 will now be described, reference being had to Figs. 2, 3, and 4 of the drawing. This mechanism comprises a casing 35 having a chamber 36 in one end thereof and a chamber 37 in the other end thereof. The chambers 36 and 37 are connected by a bore 38 of reduced diameter. A valve seat 39 is located at one end of the bore 38 and a similar valve seat 40 is located at the other end of the bore 38. The chamber 36 is closed by a removable cap 41 and the chamber 37 is closed by a removable cap 42. A sleeve 43, having end walls 44 and 45, is carried by the cap 41 and extends into the chamber 36. A valve stem 46 which is slidably mounted in a bushing 47 carried by the end wall 45 of the sleeve 43, extends from the chamber 36 into the sleeve 43. A valve disc 48 of suitable material is secured to one end of the valve stem 46 within the chamber 36, and a metal disc 49 is secured to the other end of the stem 46 within the sleeve 43. A spring 50 disposed about the valve stem 46 between the valve disc 48 and the end wall 45 of the sleeve 43 normally holds the valve disc 48 against the valve seat 39. A horseshoe magnet 51 is secured to one end of a hollow exteriorly threaded stud 52 which extends out through aligned apertures in the end wall 44, of the sleeve 43, and in the end of the cap 41. A nut 53 screwed onto the outer portion of the stud 52 securely holds the magnet 51 and the sleeve 43 in place. The legs of the magnet 51 have a winding 54 thereon one end of which is connected to the tube 26 and the other end of which is connected to the wire 27 in the tube 26. The tube 26 is inserted into the hollow stud 52 and is held in place by a screw fitting 52a. A sleeve 55 is screwed into a threaded recess in the end of the cap 42, as indicated at 56, and extends into the chamber 37 a slight distance. One end of the sleeve 55 is closed by an end wall 57, and the other end which is open registers with a circular aperture 58 in the end wall of the cap 42. A plug 59 is slidably mounted in the sleeve 55 and extends out through the aperture 58 in the cap 42. The outer end of the plug 59 has a reduced extension 60 formed integral therewith, providing an annular shoulder 61 around the extension 60 at the outer end of the plug 59. A stem 62 which is secured to the inner end of the plug 59 extends out through an aperture 63, in the end wall 57 of the sleeve 55, and through the chamber 37 and into the bore 38. The stem 62 has a collar 64 rigidly secured thereon between the end wall 57 and the outer end of the stem. A valve disc 65 of suitable material is slidably mounted upon the stem 62 between the end wall 57 of the sleeve 55 and the collar 64. The valve disc 65 is adapted to engage the valve seat 40 to cut off the flow of gas into the chamber 37 during the initiation of operation as will be hereinafter described. A compression spring 66 disposed about the stem 62 between the end wall 57 and the valve disc 65 normally yieldingly holds

the valve disc 65 against the collar 64. A compression spring 67 which is stronger than the spring 66 is disposed about the stem 62 within the sleeve 55 between the inner face of the end wall 57 and the inner end of the plug 59. The spring 67 is operative to return the plug 59, stem 62 and valve disc 65 from the position shown in Fig. 3 back to their normal position as shown in Fig. 2, against the resistance of the spring 66. A port 68 in the casing 35 provides communication between the chamber 36 and the conduit 3 to allow gas to flow from the main control valve 4 into the chamber 36. During normal operation of the main burner 1 gas flows from the chamber 36 through the reduced intermediate bore 38 and into the chamber 37. A port 69 which establishes communication between the conduit 17 and the bore 38 is provided to supply gas to the pilot burner 16; and a port 70 establishes communication between the chamber 37 and the connector 10 to permit the flow of gas from the chamber 37 to the main burner 1 through the oven temperature control valve and the conduit 3.

The safety control valve mechanism 5 is operatively connected to the solenoid 22 by a yoke 72 and a link 73. The yoke 72 which encompasses the safety control valve mechanism 5 as shown in Fig. 4 comprises a pair of spaced parallel arms 74 which are connected together at one end by a bridge 75. The bridge 75 has an aperture 76 therein through which the reduced end 60 of the plug 59 extends with the inner face of the bridge engaging the shoulder 61 between the plug 59 and the reduced extension 60 thereof. The other ends of the arms 74 terminate in a pair of spaced parallel ears 77 to and between which one end of the link 73 is pivotally connected. The other end of the link 73 is pivotally connected to the movable core 78 of the solenoid 22 as indicated at 79.

In order to adapt the mechanism for automatic control by a time control mechanism 99 I provide a by-pass conduit 101 around a portion of the conduit 3 between the manifold M and the safety control valve mechanism 5 and I locate the main control valve 4 at a junction of the main conduit 3 and the by-pass 101 so that in one open position of the valve 4 fuel will be directed straight through the conduit 3 and in the other open position thereof fuel will be directed to the by-pass conduit 101. In the by-pass 101 I interpose a normally closed solenoid valve 102 which is adapted to be opened and maintained open by a solenoid 103 when the solenoid 103 is energized. I also provide a supplemental master control switch 104 which is also associated with the main control valve 4 and is adapted to be closed by the setting of the main control valve in position to direct fuel through the by-pass conduit 101 and to be opened when the main control valve is turned to off position. The switch 104 is actuated by the cam 25 on the main control valve stem 3 and a link 105. The time control mechanism 99 is of standard construction and comprises a self-starting electric clock 91, a normally open switch 92 and mechanism responsive to the clock 91 and operative to close the switch 92 at a predetermined set time and to reopen the switch 92 at a predetermined set later time. Operating current is constantly supplied to the clock 91 through the leads 93 and 94. The time control mechanism is set as desired by the buttons 95, 96 and 97. The button 95 is provided to set the time at which it is desired to initiate operation of the burner 1; the button 96 is pro-

vided to set the time at which it is desired to terminate operation of the burner 1, and the button 97 is provided to set the time control mechanism 99 in operative condition. After each automatic operation the time control mechanism automatically returns to its normal inoperative condition and must be reset for each subsequent automatic operation of the burner 1. The time control switch 92 is disposed in series with the supplemental master switch 104 and with the normally closed thermostatic switch 21. The time control switch is also disposed in series with the solenoid 103 which actuates the valve 102.

The operation of the apparatus will now be described in connection with Fig. 1 which includes a wiring diagram showing the electrical circuits of my improved ignition and control apparatus with a time control mechanism incorporated therein. To initiate the operation of the oven burner 1 under manual control it is only necessary to set the oven temperature control valve 6 to the desired temperature and to manually turn the main control valve 4 from the off position to the on position, shown in Fig. 5, which directs the fuel straight through the conduit 3 from the manifold M to the safety control valve mechanism 5. After that the ignition and operation of the burner are automatically controlled until the operation of the burner is terminated by manually turning the main control valve 4 from the on position to the off position. As the main control valve 4 is turned from the off position to the on position the master switch 23 is simultaneously closed by the cam 25 and lever 24. After the main control valve has been opened gas can flow from the manifold through the main control valve 4 and into the chamber 36 of the safety control valve mechanism 5, the various parts of which are in the position shown in Fig. 2. But the gas can go no farther since the valve disc 48 is being held against the valve seat 39 by the spring 50, thus closing the only exit from the chamber 36. As soon as the switch 23 is closed current flows from one side 113 of the line through the lead 111 to the switch 23 and thence through the lead 112 to the switch 21. From the switch 21 the current flows through the lead 113 to the electrical resistance ignition element 18, thence through the ignition element 18 and back to the other side 114 of the line through the lead 115, thus completing a circuit through the ignition element 18 which energizes it and renders it operable to ignite the pilot burner 16 as soon as gas is supplied thereto. From the normally closed switch 21 the current also flows through the leads 113 and 116 to the solenoid 22, thence through the winding of the solenoid and back to the other side 114 of the line through the leads 117 and 115, thus completing a circuit which energizes the solenoid 22. The energization of the solenoid 22 causes it, through the link 73 and yoke 72, to shift the various parts of the safety control valve mechanism from the position shown in Fig. 2 to the position shown in Fig. 3. In this position the valve disc 48 is held away from the valve seat 39 and the metal disc 65 is held against the ends of the legs of the magnet 51 by stem 62 acting against the resistance of the spring 66. This allows gas to flow from the chamber 36 into the bore 38 and thence through the port 68 and conduit 17 to the pilot burner 16 where it is ignited by the ignition element 18. But the gas cannot yet flow to the main burner 1 since the valve disc 65 is being held against the seat 49 by the spring 66 which cuts off communication between the bore

38 and the chamber 37. As soon as the pilot burner 16 is ignited it projects a flame against and heats both the thermocouple 20 and the thermostatic element 19. The heating of the thermocouple 20 generates a minute current which energizes the magnet 51 sufficiently for it to hold the metal disc 49 and the stem 46 and valve disc 48 secured thereto in the position shown in Fig. 3 against the pressure of the spring 50 after the disc 49 has been moved into engagement with the magnet 51 by the solenoid 22. But the magnet 51 when energized by the thermocouple 20 is not strong enough to attract and withdraw the metal disc 49, and the stem 46 and valve disc 48 secured thereto, from the position shown in Fig. 2 to the position shown in Fig. 3. It can only hold these parts in this position after they have been moved thereto by the solenoid 22 through the medium of the link 73, yoke 72, plunger 59 and stem 62. After the thermostatic element 19 has been heated sufficiently, which is after the thermocouple has energized the magnet 51, it will open the normally closed switch 21, breaking the circuit to and de-energizing both the ignition element 18 and the solenoid 22. After the pilot burner has been ignited there is no further need to maintain the ignition element energized. As soon as the solenoid 22 is de-energized the spring 67 will return the plunger 59, stem 62 and valve disc 48 back from the position shown in Fig. 3 to the position shown in Fig. 2 against the pressure of the spring 66. The valve disc 48 will be held in the position shown in Fig. 3 by the magnet 51. Communication is then established between the chambers 36 and 37 through the bore 38. Gas will then flow from the chamber 36 into the chamber 37 through the bore 38. From the chamber 37 gas will flow through the oven temperature control valve 6 and conduit 3 to the main burner 1 where it will be ignited by the pilot burner 16. The apparatus is now operating normally, and in the absence of any abnormal conditions it will continue to do so, provided the pilot burner remains ignited, until the supply of gas to both the pilot burner and the main burner is cut off by the manual closing of the main control valve 4.

In the event the pilot burner 16 is extinguished for any reason during operation, the thermocouple 20 will cool in a few seconds and de-energize the magnet 51. The de-energizing of the magnet 51 will allow the spring 50 to move the valve disc 48 back into engagement with the valve seat 39, as shown in Fig. 2, which will cut off the flow of gas from the chamber 36 into the bore 38 and chamber 37, and from them to the pilot light 16 and the main burner 1. The burner 1 will then be extinguished along with the pilot burner. As soon as the thermostatic element 19 cools it will close the switch 21 which will energize both the ignition element 18 and the solenoid 22 as previously described since the main control valve 4 is still open and the switch 23 is closed. The pilot burner 16 will then be re-ignited and the rest of the apparatus will again function as described, provided there is gas available. If no gas is available everything will remain in condition to ignite the pilot burner and reinitiate operation as soon as gas is again available. In the event of either a momentary or prolonged power failure during operation, the apparatus will continue to operate normally until terminated by the manual closing of the main control valve, provided of course that all other conditions are normal. In order to operate the apparatus under

5 manual control during a prolonged power failure which occurred prior to operation, it is only necessary to hold a match to the pilot burner 16 and manually move the plunger 59 from the position shown in Fig. 2 to the position shown in Fig. 3 and hold it in this position a sufficient time for the thermocouple 20 to become heated, after which the plunger 59 may be released and allowed to be returned to its initial position by the spring 67. The apparatus will then continue to function normally as described under the control of the pilot burner 16 and the oven temperature control valve 6, until operation is terminated by the manual closing of the main control valve 4.

15 When it is desired to initiate and terminate operation of the burner 1 automatically, the time control mechanism 90 is set to initiate operation at the desired time and to terminate operation after the burner 1 has been operating the desired length of time; and the main control valve 4 is turned to the position shown in Fig. 6 which directs fuel into the by-pass 101 and also closes the supplemental master switch 104. At this time fuel cannot flow to the main and pilot burners 1 and 16 since the valve 102 in the by-pass conduit 101 is closed. Then at the set time the time control mechanism 90 will close the switch 92, after which current will flow from one side 110 of the line through the lead 116, switch 92, lead 118, solenoid 103 and back to the other side 114 of the line through the leads 120 and 115 energizing the solenoid 103. Current will also flow from the switch 92 through the leads 119 and 121, supplemental master switch 104 and the leads 122 and 112 to the switch 21. From the switch 21 the current will also flow through the electric ignition element 18 and the solenoid 22 and back to the other side 114 of the line as previously described, thus energizing the electric ignition element 18 and the solenoid 22. The solenoid 103 upon energization opens the normally closed valve 102 in the by-pass conduit 101 and will maintain the valve 102 open as long as the solenoid is energized. Fuel will now flow through the by-pass conduit 101 to the safety control valve mechanism 5 and from there to the pilot burner 16 since the solenoid 22 is holding the safety control valve mechanism as shown in Fig. 3. The pilot burner will then be ignited by the electric ignition element 18 after which the apparatus will function as described, in connection with manual control of the burner 1, until the time control mechanism opens the switch 92. The opening of the switch 92 will break the circuit to and de-energize the solenoid 103 after which the valve 102 will automatically close and completely cut off the supply of fuel to both the main burner and the pilot burner, thus terminating operation.

50 As an example of the automatic operation of the burner 1 let us assume that it is desired to initiate operation of the burner 1 at 3 o'clock and to terminate operation thereof at 6 o'clock. The time control mechanism is then set by the button 95 to initiate operation of the burner 1 at 3 o'clock according to the clock 91, and by the button 96 to terminate operation thereof at 6 o'clock. The time control mechanism is then set in operative condition by button 97 and the main control valve is turned as shown in Fig. 6 to direct fuel through the by-pass conduit 101. Then at 3 o'clock by the clock 91 the time control mechanism will close the switch 92 which will through the solenoid 103 and valve 102 initiate operation of the burner 1. At 6 o'clock by the

55

60

65

70

75

clock 91 the time control mechanism will open the switch 92 and terminate operation of the burner 1. Now let us assume that with the time control 90 set as above, there is a temporary current failure of half an hour after the burner 1 has been operating one hour. That would be at four o'clock by the clock 91. The current failure will stop the clock 91 and de-energize the solenoid 103. The valve 102 will then close and cut off the supply of fuel to the burner 1, thus stopping its operation. After half an hour the current comes back on which re-energizes the solenoid 103, since the switch 92 is still closed, and starts the clock 91 operating again. The re-energization of the solenoid 103 opens the valve 102 and starts the burner 1 operating again. Then two hours later, at six o'clock by the clock 21, the time control mechanism will open the switch 92 and terminate operation of the burner 1. From this it will be seen that the burner 1 operated just three hours, the set time, even though due to the half hour current failure the elapsed time from the beginning of the operation of the burner 1 until the final termination thereof was three and one-half hours.

In Fig. 7 I have shown a slightly modified means for automatically controlling the operation of the burner 1. In this form of the invention I eliminate the supplemental master switch 104 and I place the normally open time control switch 92 in series with the normally closed switch 21 by connecting the terminal 125 of the switch 92 to the lead 112 by a lead 126. Then with the main control valve 4 set for automatic operation, as shown in Fig. 6, when the time control mechanism 90 closes the switch 92 current will flow from the side 110 of the line through the lead 118 to the switch 92 and from the switch 92 through the leads 126 and 112 to the switch 21; and through the lead 119 to the solenoid 103. From the switch 21 the current will flow through the electric ignition element 18 and the solenoid 22 and back to the other side 114 of the line as described in connection with Fig. 1; and from the solenoid 103 back to the side 114 of the line through the leads 120 and 115. Otherwise the construction and operation of this form of the invention is the same as that shown in Fig. 1 and the same reference characters have been applied to like parts in the two forms. The description of the construction and operation of the invention as shown in Fig. 1 applies also to the form of the invention shown in Fig. 7.

In Fig. 8 I have shown still another slightly modified means for automatically controlling the operation of the main burner 1. In this form of the invention I connect the terminal 125 of the switch 92 to the terminal 127 of the switch 104 by the lead 121 and I connect the terminal 128 of the switch 104 to the solenoid 103 by the lead 129 and I eliminate the lead 119 which connects the terminal 125 of the switch 92 to the solenoid 103. This places the switch 104 in series with the switch 92 and solenoid in one circuit as well as in series with the switch 92 and switch 21 in another circuit. Then with the main control valve set for automatic operation, as shown in Fig. 6, when the time control mechanism 90 closes the switch 92 current will flow from the side 110 of the line through the lead 118 to the switch 92 and from the switch 92 through the lead 121 to the switch 104. From the switch 104 current will flow through the lead 129 to the solenoid 103 and from the solenoid 103 through the leads 120 and 115 back to the other side 114 of the line.

Current will also flow from the switch 104 through the switch 21, electric ignition element 18 and solenoid 22 and back to the line as described in connection with Fig. 1. Otherwise this form of the invention is the same as that shown in Fig. 1 and the same reference characters have been applied to like parts in the two forms. The description of the construction and operation of the invention as shown in Fig. 1 applies also to the form of the invention shown in Fig. 8.

In the form of the invention shown in Fig. 1, one might set the time control 90 for automatic operation and forget to set the main control valve 4, in which case the time control would close the switch 92 at the set time and reopen it at the set later time. The solenoid 103 would be energized and the valve 102 held open during the time the switch 92 was closed, but since the main control valve 4 was closed and the supplemental master switch 104 was open during this time the main burner would not operate. However, this would not harm the mechanism as the solenoid 103 could be energized indefinitely without harm.

In the form of the invention shown in Fig. 7 if the time control 90 was set for automatic operation and the main control valve 4 was left closed and the switch 104 open the solenoids 22 and 103 and electric ignition element 18 would be energized during the time the switch 92 was held closed by the time control 90, but since the main valve 4 was closed the burner would not operate. Under these circumstances the electric ignition might burn out. This form of the invention has the advantage of the elimination of the switch 104, but it also has the disadvantage that there is a possibility of burning out the electric ignition element 18.

In the form of the invention shown in Fig. 8 both the switch 92 and the switch 104 must be closed before either the solenoid 103, the solenoid 22, or the electric ignition element 18 can be energized. The time control 90 might be set for automatic operation and the main control valve 4 left closed, which would leave the switch 104 open, but neither the solenoids nor the electric ignition element would be energized.

From the foregoing it will be apparent to those skilled in the art that I have provided very simple and efficient mechanisms for accomplishing the objects of the invention.

It is to be understood that I am not limited to the specific constructions shown and described herein as various modifications may be made therein within the scope of the appended claims.

What is claimed is:

1. In an automatic ignition and control apparatus of the character described, the combination of a main burner, a pilot burner operative to ignite said main burner, an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said main burner and said pilot burner after the fuel leaves said main control valve, a solenoid operatively connected to said safety control valve.

mechanism, said solenoid being operative upon energization to set said safety control valve mechanism in condition to supply fuel to said pilot burner while cutting off the supply of fuel to said main burner and upon subsequent de-energization to set said safety control valve mechanism in condition to also supply fuel to said main burner, a normally closed switch operative to control the energization of said solenoid and said electric ignition element, a thermostatic element adapted to be heated by said pilot burner and operative to maintain said switch open when heated and closed when cool, a by-pass around a portion of said conduit, said manually operable main control valve being located at a junction of said conduit and said by-pass and having one closed position and two open positions and operative when in one open position to direct fuel straight through said conduit to said safety control valve mechanism and to said burners and when in the other open position to direct fuel through said by-pass to said safety control valve mechanism and said burner and when in closed position to completely shut off the flow of fuel to said burner, a normally closed valve in said by-pass, a second solenoid operative when energized to maintain said normally closed valve open, a normally open time control switch operative when closed to effect energization of said electric ignition element, said solenoid and said second solenoid, and a time control mechanism operative to close and open said time control switch at predetermined set times.

2. In an automatic ignition and control apparatus of the character described, the combination of a main burner, a pilot burner operative to ignite said main burner, an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said main burner and said pilot burner after the fuel leaves said main control valve, a solenoid operatively connected to said safety control valve mechanism, said solenoid being operative upon energization to set said safety control valve mechanism in condition to supply fuel to said pilot burner while cutting off the supply of fuel to said main burner and upon subsequent de-energization to set said safety control valve mechanism in condition to also supply fuel to said main burner, a by-pass around a portion of said conduit, said manually operable main control valve being located at a junction of said conduit and said by-pass and having one closed position and two open positions and operative when in one open position to direct fuel straight through said conduit to said safety control valve mechanism and said burners and when in the other open position to direct fuel through said by-pass to said safety control valve mechanism and said burner and when in closed position to completely shut off the flow of fuel to said burners, a normally closed valve in said by-pass, a second solenoid operative when energized to maintain said normally closed valve open, a normally open

master control switch, a normally open time control switch disposed in series with said master control switch and also in series with said second solenoid and when closed operative alone to energize said second solenoid and in conjunction with said master switch to energize said solenoid and said electric ignition element, a time control mechanism operative to close and open said time control switch at predetermined set times, a normally closed switch which is operative when opened to de-energize said solenoid and said electric ignition element, and means responsive to said pilot burner and operative to open said normally closed switch after said pilot burner has been ignited by said electric ignition element.

3. An automatic ignition and control apparatus as defined in claim 2 in which said means comprises a thermostatic element adapted to be heated by said pilot burner and operative when heated to maintain said normally closed switch open and when cool to maintain said normally closed switch closed.

4. In an automatic ignition and control apparatus of the character described, the combination of a main burner, a pilot burner operative to ignite said main burner, an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said main burner and said pilot burner after the fuel leaves said main control valve, a solenoid operatively connected to said safety control valve mechanism, said solenoid being operative upon energization to set said safety control valve mechanism in condition to supply fuel to said pilot burner while cutting off the supply of fuel to said main burner and upon subsequent de-energization to set said safety control valve mechanism in condition to also supply fuel to said main burner, a by-pass around a portion of said conduit, said manually operable main control valve being located at a junction of said conduit and said by-pass and having one closed position and two open positions and operative when in one open position to direct fuel straight through said conduit to said safety control valve mechanism and to said burners and when in the other open position to direct fuel through said by-pass to said safety control valve mechanism and said burners and when in closed position to completely shut off the flow of fuel to said burners, a normally closed valve in said by-pass, a second solenoid operative when energized to maintain said normally closed valve open, switching means including a time control switch operative to effect energization of said electric ignition element, said solenoid and said second solenoid, a time control mechanism operative to open and close said time control switch at predetermined set times, and means operative to de-energize said electric ignition element and said solenoid after said pilot burner has been ignited by said electric ignition element.

5. An automatic ignition and control apparatus as defined in claim 4 in which said last

mentioned means comprises a normally closed switch, and a thermostatic element adapted to be heated by said pilot burner and operative when heated to maintain said normally closed switch open and when cool to maintain said normally closed switch closed.

6. In an automatic ignition and control apparatus of the character described, the combination of a main burner, a pilot burner operative to ignite said main burner, an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said burner and said pilot burner after the fuel leaves said main control valve, a solenoid operatively connected to said safety control valve mechanism, said solenoid being operative upon energization to set said safety control valve mechanism in condition to supply fuel to said pilot burner while cutting off the supply of fuel to said main burner and upon subsequent de-energization to set said safety control valve mechanism in condition to also supply fuel to said main burner, a by-pass around a portion of said conduit, said manually operable main control valve being located at a junction of said conduit and said by-pass and having one closed position and two open positions and operative when in one open position to direct fuel straight through said conduit to said safety control valve mechanism and to said burners and when in the other open position to direct fuel through said by-pass to said safety control valve mechanism and said burners and when in closed position to completely shut off the flow of fuel to said burners, a normally closed valve in said by-pass, a second solenoid operative when energized to maintain said normally closed valve open, a normally open master control switch, operative connections between said main control valve and said master switch through which said master control switch is closed by the setting of said main control valve to direct fuel through said by-pass, a normally closed switch disposed in series with said master switch and said electric ignition element and with said master switch and said solenoid, means operative to open said normally closed switch after said pilot burner has been ignited by said electric ignition element, a time control switch disposed in series with said master switch and in series with said second solenoid, and a time control mechanism operative to close and open said time control switch at predetermined set times, said time control switch when closed being operative alone to energize said second solenoid and in conjunction with said master switch to energize said electric ignition element and said solenoid and said normally closed switch being operative when opened to deenergize said electric ignition element and said solenoid.

7. An automatic ignition and control apparatus as defined in claim 6 in which, said means operative to open said normally closed switch after said pilot burner has been ignited by said elec-

tric ignition element comprises, a thermostatic element adapted to be heated by said pilot burner and operative when heated to maintain said normally closed switch open and when cool to maintain said normally closed switch closed.

8. In an automatic ignition and control apparatus of the character described, the combination of a main burner, a pilot burner operative to ignite said main burner an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said main burner and said pilot burner after the fuel leaves said main control valve, a solenoid operatively connected to said safety control valve mechanism, said solenoid being operative upon energization to set said safety control valve mechanism in condition to supply fuel to said pilot burner while cutting off the supply of fuel to said main burner and upon subsequent de-energization to set said safety control valve mechanism in condition to also supply fuel to said main burner, a by-pass around a portion of said conduit, said manually operable main control valve being located at a junction of said conduit and said by-pass and having one closed position and two open positions and operative when in one open position to direct fuel straight through said conduit to said safety control valve mechanism and to said burners and when in the other open position to direct fuel through said by-pass to said safety control valve mechanism and said burners and when in closed position to completely shut off the flow of fuel to said burners, a normally closed valve in said by-pass, a second solenoid operative when energized to maintain said normally closed valve open, a normally open master control switch adapted to be closed by the setting of said main control valve to direct fuel straight through said conduit, a normally closed switch in series with said master switch and said electric ignition element and with said master switch and said solenoid, means operative to open said normally closed switch after said pilot burner has been ignited by said electric ignition element, a normally open supplemental master switch adapted to be closed by the setting of said main control valve to direct fuel through said by-pass and disposed in series with said normally closed switch, a normally open time control switch disposed in series with said supplemental master switch and with said second solenoid, and a time control mechanism operative to close and open said time control switch at predetermined set times, said master switch being operative when closed to energize said electric ignition element and said solenoid, said time control switch when closed being operative alone to energize said second solenoid and in conjunction with said supplemental master switch to energize said electric ignition element and said solenoid, and said normally closed switch being operative when opened to deenergize said electric ignition element and said solenoid.

9. An automatic ignition and control apparatus as defined in claim 8 in which, said means operative to open said normally closed switch after said pilot burner has been ignited by said electric ignition element comprises, a thermostatic element adapted to be heated by said pilot burner and operative when heated to maintain said normally closed switch open and when cool to maintain said normally closed switch closed.

10. In an automatic ignition and control apparatus of the character described, the combination of a main burner, a pilot burner operative to ignite said main burner, an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said main burner and said pilot burner after the fuel leaves said main control valve, a solenoid operatively connected to said safety control valve mechanism, said solenoid being operative upon energization to set said safety control valve mechanism in condition to supply fuel to said pilot burner while cutting off the supply of fuel to said main burner and upon subsequent deenergization to set said safety control valve mechanism in condition to also supply fuel to said main burner, a by-pass around a portion of said conduit, said manually operable main control valve being located at a junction of said conduit and said by-pass and having one closed position and two open positions and operative when in one open position to direct fuel straight through said conduit to said safety control valve mechanism and said burners and when in the other open position to direct fuel through said by-pass to said safety control valve mechanism and said burner and when in closed position to completely shut off the flow of fuel to said burners, a normally closed valve in said by-pass, a second solenoid operative when energized to maintain said normally closed valve open, a normally open master control switch, a normally open time control switch disposed in series with said master control switch and said second solenoid, said master switch and said time control switch being operative when both of said switches are closed to effect energization of said electric ignition element, said solenoid and said second solenoid, a time control mechanism operative to close and open said time control switch at predetermined set times, a normally closed switch which is operative when opened to deenergize said solenoid and said electric ignition element, and means responsive to said pilot burner and operative to open said normally closed switch after said pilot burner has been ignited by said electric ignition element.

11. An automatic ignition and control apparatus as defined in claim 10 in which said means comprises a thermostatic element adapted to be heated by said pilot burner and operative when heated to maintain said normally closed switch open and when cool to maintain said normally closed switch closed.

12. In an automatic ignition and control ap-

paratus of the character described, the combination of a main burner, a pilot burner operative to ignite said main burner, an electric ignition element operative when energized to ignite said pilot burner, a conduit through which gaseous fuel is supplied to said main burner, a manually operable main control valve by which the supply of fuel to said main burner and said pilot burner is primarily controlled, a safety control valve mechanism interposed in said conduit between said main control valve and said main burner, a secondary conduit extending between said safety control valve mechanism and said pilot burner through which gaseous fuel is supplied to said pilot burner, said safety control valve mechanism being operative to control the supply of fuel to said main burner and said pilot burner after the fuel leaves said main control valve, a solenoid operatively connected to said safety control valve mechanism, said solenoid being operative upon energization to set said safety control valve mechanism in condition to supply fuel to said pilot burner while cutting off the supply of fuel to said main burner and upon subsequent deenergization to set said safety control valve mechanism in condition to also supply fuel to said main burner, a by-pass around a portion of said conduit, said manually operable main control valve being located at a junction of said conduit and said by-pass and having one closed position and two open positions and operative when in one position to direct fuel straight through said conduit to said safety control valve mechanism and said burners and when in the other open position to direct fuel through said by-pass to said safety control valve mechanism and said burner and when in closed position to completely shut off the flow of fuel to said burners, a normally closed valve in said by-pass, a second solenoid operative when energized to maintain said normally closed valve open, a normally open time control switch which is operative when closed to effect energization of said electric ignition element, said solenoid and said second solenoid, a time control mechanism operative to close and open said time control switch at predetermined set times, a normally closed switch which is operative when opened to deenergize said solenoid and said electric ignition element, and means responsive to said pilot burner and operative to open said normally closed switch after said pilot burner has been ignited by said electric ignition element.

13. An automatic ignition and control apparatus as defined in claim 12 in which said means comprises a thermostatic element adapted to be heated by said pilot burner and operative when heated to maintain said normally closed switch open and when cool to maintain said normally closed switch closed.
